(57) **CLAIM**

The ornamental design for a cremation urn, as shown and described.

DESCRIPTION

FIG. 1 is a perspective view of an urn depicting my new design.

FIG. 2 is another perspective view of the urn.

FIG. 3 is a front elevational view of the urn.

FIG. 4 is a right side elevational view of the urn.

FIG. 5 is a left side elevational view of the urn; and,

FIG. 6 is a top plan view of the urn.

The broken line showing an upper portion of the cremation urn is for illustrative purposes only and forms no part of the claimed design. The unshown bottom portion and rear portion of the cremation urn form no part of the claimed design.
